UNITED STATES PATENT OFFICE.

CHARLES MUNTER, OF NEW YORK, N. Y.

CORSET.

Application filed August 10, 1921. Serial No. 491,070.

To all whom it may concern:

Be it known that I, CHARLES MUNTER, a citizen of the United States, residing at New York city, borough of Manhattan, in the county and State of New York, have invented a certain new and useful Corset, of which the following is a specification.

This invention is a corset and relates more particularly to improvements on the corset or body conformer forming the subject matter of my prior Patent No. 848,479, of March 26th, 1907.

The corset of this prior patent has gone into extensive use and has been found to give highly superior results. However, my close observation and experiments in connection with corsets have shown that, in the case of certain individuals, advantages may be imparted to said corset by associating therewith certain adjunctive features and by modifying in certain particulars the specific lacing shown in my prior patent.

With the foregoing considerations in mind, the present invention comprises a corset wherein is embodied in the back of the corset above the lacing and at the upper end of the back opening an elastic gusset, the function of which will be hereinafter fully described. I also preferably employ a similar gusset at the lower end of the back opening and below the lacing.

Furthermore, in some instances, I find it advantageous to employ in conjunction with one or both of these gussets stay members additional to those disclosed in my prior patent, and so embodied in the corset as to properly support the figure of the wearer without undue restriction of movement. In other instances, the lacing for regulating the size of the back opening may advantageously be extended above the waistline. It will be observed that the gusset is positioned in a cut-out portion of the corset sections, the body of each section being cut away a substantial distance to each side of the opening so that the gusset bridges the cut-off portion and extends across the opening. With this construction the opening may be practically closed, as shown in Fig. 2, and the edges of the sections brought together without puckering or folding the elastic of the gusset, which is confined to the cut-out portion above the opening.

Another feature which I have found it desirable to employ at times is to discontinue the front stays which extend along the

edge of the front opening of the corset a short distance above the lower edge of the corset and to lace that portion of the front opening of the corset below the lower edge of said stays.

Features of the invention, other than those adverted to, will be apparent from the hereinafter detailed description and claims, when read in conjunction with the accompanying drawings.

The accompanying drawings illustrate different practical embodiments of the invention, but the constructions therein shown are to be understood as illustrative, only, and not as defining the limits of the invention.

Figure 1 is a front view of the corset in position on the wearer.

Figure 2 is a back view of the corset positioned on the wearer; and,

Figure 3 is a fragmental showing of the rear of the corset at the portion thereof including the lower part of the back opening, said figure illustrating a slightly modified form of the corset at the location illustrated.

The corset of the present invention is preferably made in two sections 1 and 2, the upper and lower edges of which are shaped to the desired contour, provided with suitable binding. The upper parts of both sections are secured together at the back of the corset by a gusset 3 of elastic material and the back opening 4 of the corset extends downwardly to the lower edge of the corset from the bottom of the gusset 3. Along either edge of the back opening 4, both of the sections 1 and 2 are provided with eyelets 5 and laces 6 are threaded through the eyelets 5 and secured at their opposite ends to belt sections 7 and 8, one of which is provided with a buckle 9 to permit the belt to be secured about the body of the wearer under the desired tension to properly adjust the lacing and regulate the size of the back opening so that the corset will properly conform to the figure. The front edges of the sections 1 and 2 are adapted to be detachably united when the garment is wrapped about the figure by the usual female and male fastening devices 10 and 11, respectively, but the lower portion of the front opening is preferably provided for a short distance up from the bottom of the corset with eyelets 12, along either side thereof for the reception of a lace 13 by means of which such lower portion of the front opening may be laced together if desired. In some in-

stances, however, the eyelets 12 are omitted and the fastening devices 10 and 11 extended entirely to the bottom of the corset.

The corset of this invention may embody 5 any number of stays desired, but for the purpose of illustration, I have shown them distributed throughout both sections 1 and 2 in a manner which I find highly advantageous. For example, it will be noted that 10 there are stays 16 and 17 extending in substantially parallel relation along the opposite sides of each row of eyelets 5 adjacent the back opening and additional stays may be positioned along or adjacent the front 15 edges of the corset. Other stays 18 are preferably disposed throughout the corset, so as to extend downwardly from the upper edge thereof toward the lower edge.

It will be noted that certain of these 20 later stays extend substantially to the lower edge of the garment, while others are discontinued at points above the lower edge. The reason for this arrangement is to give 25 unrestricted movement of the body and particularly to the limbs when the wearer assumes sitting posture. For example, I find that if the stays over the hips are shortened slightly or graduated in length as shown, that the corset will not bind as would be 30 the case if the stays were extended entirely to the bottom of the corset, and, in like manner, this graduating of the length of the stays may be carried out in the front of the corset.

25 The corset as described embodies many advantageous features. For example, it will be noted that by positioning the elastic gusset at the upper portion of the back opening, the upper portion of the corset 40 will automatically conform to the size of the portion of the body which it overlies, so that in making corsets embodying this feature, great nicety of cutting and fitting is rendered unnecessary. Moreover, the large 45 variety of sizes which it is necessary to carry in stock if the upper portion of the back of the corset is rigid, is not necessary when the elastic gusset is employed, since this gusset will compensate for slightly 50 varying sizes and assure a snug conformation of the garment in all cases.

Furthermore, the employment of the elastic gusset 3 imparts to the corset all of the 55 advantages of a corset open from top to bottom in the back, while obviating the long recognized disadvantages in the open back corset. The gusset 3 closely conforms to the portion of the body which it overlies and is soft and pliable so that chafing 60 thereby does not occur.

In the form of the invention illustrated in 65 Figures 1 and 2, the back opening 4 extends from the gusset 3 directly to the bottom of the lower edge of the corset, though, if desired, I may modify this construction by

providing an elastic gusset at the lower end of the back opening. In other words, I provide an elastic gusset at both the top and bottom of the corset in the medial line of the back and form a back opening between 70 said gussets with suitable lacing for regulating the size of the back opening. Thus in Figure 3 of the drawings, a fragmental showing is made illustrating a construction wherein the lower portion of the back opening is closed by an elastic gusset 20. The gusset 3 may be employed without the gusset 20 or vice versa. A particular style of lacing 6 has been shown in the drawing, as 75 illustrative, and that shown is preferred in practice, though any form of lacing desired 80 may be used for regulating the size of the back opening without departing from this invention.

It will be noted that both the upper and lower bindings of the corset are shown as 85 broken, adjacent the flexible gussets 3 and 20, so as to permit free extension of such gussets, in order that the corset may more efficiently conform to the body. This is the 90 preferred manner of making the corset, though if desired, the bindings referred to may extend uninterruptedly across the base of the gusset. It will be observed that both 95 of the gussets are confined to their respective cut-away portions, the bottom gusset being positioned in a portion cut away from the body of each corset section; manual adjustment of the corset along the waist line 100 being permitted independently of the elastic, and the elastic functioning at the ends of the corset without effect by the manual adjustment made by the lacing.

While all the specific features described 105 may be embodied in the same corset, yet, in individual cases, I may dispense with one or more of said features or use them in other environments. Accordingly, I desire it to be understood that the invention is as 110 broadly novel as is commensurate with the appended claims.

Having thus fully described the invention, what I claim as new and desire to secure by Letters Patent is:

1. A corset provided in the upper portion 115 of substantially the medial line of the back thereof with a cut-out portion, and having a back opening extending downwardly from the cut-out portion across and below the waist line to form two corset sections, the 120 cut-out portion extending across said opening and a substantial distance beyond the edge of and into the body of each section, an elastic gusset positioned in and bridging 125 said cut-out portion, said gusset being substantially confined to said cut-out portion above said opening and extending a substantial distance to each side of the opening, the gusset automatically conforming 130 this portion of the corset to the bust of the

wearer while at the same time permitting a yielding action, lacings associated with the back opening, the upper end of said lacings terminating at approximately the lower edge of said gusset so as not to interfere with the functioning of the latter, said lacings extending across the waist line, and operating belts secured to said lacings and extending around the corset to the front of the same whereby non-yielding manual adjustment of the corset at the waist line may be obtained.

2. A corset provided in the upper portion of substantially the medial line of the back thereof with a cut-out portion, and having a back opening extending downwardly from the cut-out portion to form two corset sections, the cut-out portion extending across said opening and a substantial distance beyond the edge of and into the body of each section, an elastic gusset positioned in and bridging said cut-out portion, said gusset being substantially confined to said cut-out portion above said opening and extending a substantial distance to each side of the opening, the gusset automatically conforming this portion of the corset to the bust of the wearer while at the same time permitting a yielding action, lacings associated with the back opening, the upper end of said lacings terminating at approximately the lower edge of said gusset so as not to interfere with the functioning of the latter, and operating belts secured to said lacings and extending around the corset to the front of the same whereby non-yielding manual adjustment of the corset at the waist line may be obtained.

In testimony whereof I have signed the foregoing specification.

CHARLES MUNTER.
